COMBINED TRAY, LOG, AND SALT AND PEPPER SHAKER

William E. Copeland, Kansas City, Kans.

Application September 23, 1949, Serial No. 5,141

Term of patent 3½ years

(Cl. D44—22)

To all whom it may concern:

Be it known that I, William E. Copeland, a citizen of the United States, residing at Kansas City, in the county of Wyandotte and State of Kansas, have invented a new, original, and ornamental Design for a Combined Tray, Log, and Salt and Pepper Shaker, of which the following is a specification, reference being had to the accompanying drawings, forming a part thereof.

Figure 1 is a side elevational view of a combined tray, log, and salt and pepper shaker, showing my new design;

Figure 2 is a top plan view thereof;
Figure 3 is an end elevation thereof.

I claim:

The ornamental design for a combined tray, log, and salt and pepper shaker, as shown.

WILLIAM E. COPELAND.
